UNITED STATES PATENT OFFICE

EMIL GMINDER, OF REUTLINGEN, GERMANY

EXTRACTION OF FOREIGN BODIES FROM SPINNING MATERIAL

Application filed June 27, 1929, Serial No. 373,987, and in Germany January 31, 1928.

In preparing fibrous material for subsequent treatment, for instance in spinning, it is necessary to remove such foreign bodies as seeds, stalks, leaves, burrs, short fibres, etc. 5 The coarser foreign bodies are ordinarily removed by beater tools or similar devices, and the finer foreign bodies are removed by a carding process.

In the usual practice the foreign bodies 10 are worked from the upper side of a drum into so-called covers, and removed therefrom either continuously or intermittently, or they are thrown off by the rotation of the working or turning rollers as in a flax carding machine. This is practical only when the working and turning rollers are mounted on the under side of the drum.

The main object of my invention is to provide an improved means for removing coarse 20 and fine foreign bodies from the material on the drum surface, and so designed and so constructed that it may operate on the upper side of the drum or at any point desired, or at as many points desired around the entire circumference of the drum.

In carrying out my invention I provide a grate directly beyond each set of working and turning rollers, and provide in front of this grate a free space for the continuous 30 removal of the foreign bodies thus extracted.

In the accompanying drawing I have illustrated somewhat diagrammatically a construction embodying my invention, the single figure being an end view of the working parts.

35 In the construction illustrated there is provided a drum 10 which has a card covering, that is, its outer surface is provided with a multiplicity of small steel points or needles in which the fibers catch, and which pull the fibers along. In connection with this drum there are employed one or more sets of turning or working rollers. I have illustrated three such sets, including turning rollers 11, 12 and 13, and working rollers 14, 15 and 40 16. These rollers are driven and their outer surfaces are covered with steel points or needles. The turning rollers 11, 12 and 13 take the material off the working rollers and pass it back to the drum so that the material 45 passes through several times. The construc-

tion of such turning and working rollers is in accordance with common practice in machines of this general type.

In carrying out my invention I provide a free space 17 beyond one of the working rollers, and into which the coarser materials are thrown by centrifugal force from the adjacent working roller, for instance, the working roller 15. Beyond this free space there 55 is a grate 18 which is preferably in the form of a stationary iron rail positioned closely adjacent to the path of movement of the needles on the drum, so that the foreign bodies which still cling to the fibres are stripped off.

Beyond the grate bar 18 is a plate 19, and disposed above this plate is a brushing device which conveys to the outer edge of the plate the material which passes on to the plate from the grate bar, as well as the material which is thrown on to the plate by the working roller 15. This brushing device may be of any suitable character, but is shown as a belt 20 mounted on a pair of rollers 21-21, so that the under run of the belt is 60 approximately parallel to the plate 19. The belt has brushes, leather strips, or other projecting members which engage the foreign material and brush it to the free edge of the plate. 65

The plate 19 may serve as a protecting plate for the turning and working rollers 13 and 16, and it may also serve for delivering the material to a trough 22 in which there is mounted a conveyor 23 extending across the 70 full width of the machine. This trough and conveyor may be located at one side of the drum directly below a grate bar 24 so that the trough receives the foreign bodies thrown off by centrifugal force by the working roller 16 and the material removed by the grate bar 24. Also it is mounted directly below the 75 end of the plate 19 so that it receives the material brushed from the plate by the brushing device 20.

When the working and turning rollers are on the under or downwardly moving side of the drum a protecting plate and brushing device is not necessary, as the foreign material 80 may be delivered directly into a trough 22, 85 100

but when the grate bar and working roller are on the top of the machine the protecting plate and brushing device are employed to conduct the material to such a point that it will not fall back on to the drum.

5 Having thus described my invention, what I claim as new and desire to secure by Letters Patent is:

1. An apparatus for the extraction of foreign bodies from fibres, including a carding drum, a turning roller, a working roller receiving fibre from the turning roller and adapted to throw out coarse material by centrifugal force, and a grate bar adjacent to the 10 surface of the drum and disposed beyond said working roller to leave a free space through which the coarse material may be thrown from said working roller.

2. An apparatus for the extraction of foreign bodies from fibres, including a carding drum, a pair of rollers including juxtaposed turning and working rollers, a second pair of rollers including juxtaposed turning and working rollers, a grate bar between the 15 first mentioned working roller and the second mentioned turning roller and spaced from the former to permit material to be thrown by centrifugal force from the first mentioned working roller, and a plate extending from said grate bar.

3. An apparatus for removing foreign bodies from fibres, including a carding drum having a plurality of sets of turning and working rollers spaced apart, each working 20 roller being adapted to throw out coarse material by centrifugal force, and grate bars between successive sets, adjacent to the carding drum and spaced from the preceding working roller to permit said outward throwing of the coarse material.

4. An apparatus for removing foreign bodies from fibres, including a carding drum, having a plurality of sets of turning and working rollers spaced apart, and grate bars 25 between successive sets, all of said sets being upon the upper side of the drum, and each grate bar being spaced from the preceding working roller to permit the coarse material to be thrown out by centrifugal force by the 30 working roller.

5. An apparatus for the extraction of foreign bodies from fibrous material, including a carding drum, two spaced sets of turning and working rollers upon the upper side of 35 the drum, and a protecting plate disposed over one of said sets and spaced from the preceding working roller, whereby the last mentioned working roller may throw coarse material by centrifugal force onto said plate 40 and prevent it from returning to said carding drum.

Signed at Stuttgart, Germany, this 12th day of June, 1929.

EMIL GMINDER.
